UNITED STATES PATENT OFFICE.

WILLIAM B. HARRELL, OF BALDWIN, FLORIDA.

TREAD DEVICE.

1,149,912.

Specification of Letters Patent. Patented Aug. 10, 1915.

Application filed March 18, 1914. Serial No. 825,587.

To all whom it may concern:

Be it known that I, WILLIAM B. HARRELL, a citizen of the United States, residing at Baldwin, in the county of Duval and State 5 of Florida, have invented new and useful Improvements in Tread Devices, of which the following is a specification.

The invention relates to tread devices, and more particularly to the class of combined 10 easy walking and rolling devices.

The primary object of the invention is the provision of a device of this character wherein walking is rendered easy and the user can coast down grade, the device being 15 of novel form and is readily and easily applied to the user.

Another object of the invention is the provision of a combination device of this character which is extremely simple in construction and inexpensive in manufacture. 20

With these and other objects in view, the invention consists in the construction, combination and arrangement of parts as will be hereinafter fully described, illustrated in 25 the accompanying drawing, and pointed out in the claim hereunto appended.

In the drawing: Figure 1 is a perspective view of a device applied to the user and ready for coasting. Fig. 2 is a side elevation, showing the wheels raised with the device ready for use in walking. Fig. 3 is a 30 vertical transverse sectional view through one of the devices. Fig. 4 is a detail view showing the adjustable connection of the wheel with the standard.

Similar reference characters indicate corresponding parts throughout the several views in the drawing.

Referring to the drawing in detail, the 40 combination device comprises a pair of similarly constructed foot and leg attachments, each comprising a sole and heel plate 5 carrying the usual adjustable sole and heel clamps 6 and 7, respectively, for the fastening of the said plates to the shoe of the user. In addition to the clamps this plate 5 has fixed thereto adjustable straps 8 which assist in fastening the plate to the shoe. 45

Suitably fixed to and depending from the

plate 5 are a series of coiled compression 50 springs 9 which also are fixed to a tread plate 10 which is adapted to yield when contacting with the ground, the springs 9 serving to yieldably support the tread plate 10 and also to absorb shocks and jars incident to the act of walking by the user. 55

Suitably fixed to the plate 5 and adapted to lie at the outer side of the leg of the user is a brace rod 11, to the uppermost end of which is fixed an adjustable strap 12 which 60 is adapted to be fastened about the leg just below the knee to brace the ankle and foot. Slidably connected to the brace rod 11 is a clip 13 carrying an outwardly projected axle 14 on which is journaled a tired bicycle 65 wheel 15, which is of the ordinary well-known construction, the clip 13 being provided with a suitable fastening device 16 which locks the said clip in adjusted position so that the wheel 16 can be brought in 70 contact with the ground and the tread plate 10 elevated the desired distance above the same, thus enabling the user to coast on down grade.

From the foregoing it is thought that the 75 construction and manner of use of the device will be clearly understood, and therefore a more extended explanation has been omitted.

What is claimed is:—

A device of the class described comprising a foot plate, a standard rising from one side thereof and having a leg embracing ring, clips mounted on the plate and adapted for locking engagement with the shoe of a 80 wearer, a plurality of resilient springs fixed to the plate and depending therefrom, a tread plate secured to the springs and resiliently supported thereby, and a wheel 85 having its axle adjustably connected to the standard to bring the tread of the wheel or the tread plate in contact with the ground. 90

In testimony whereof I affix my signature in presence of two witnesses.

WILLIAM B. HARRELL.
